UNITED STATES PATENT OFFICE.

WILLIAM H. UPTON, OF NEW YORK, N. Y.

DESIGN FOR A CASING FOR VACUUM-CLEANERS.

56,393.

Specification for Design.

Patented Oct. 5, 1920.

Application filed July 9, 1919. Serial No. 309,792. Term of patent 14 years.

To all whom it may concern:

Be it known that I, WILLIAM H. UPTON, a citizen of the United States, and resident of the borough of Manhattan, in the city and State of New York, have invented a new, original, and ornamental Design for a Casing for Vacuum-Cleaners, of which the following is a specification, reference being had to the accompanying drawing, forming part thereof.

An embodiment of my new design for a casing for vacuum cleaners is shown in the accompanying drawing, in which—

Figure 1 represents a top plan view of my casing for a vacuum cleaner.

Fig. 2 represents a front elevation of the same, and

Fig. 3 represents a side elevation of the same.

I claim:

The ornamental design for a casing for vacuum cleaners, substantially as shown.

In testimony that I claim the foregoing as my invention, I have signed my name this 19 day of June, 1919.

WILLIAM H. UPTON.
